DESIGN FOR A DOLLY

Charles S. McCann, Racine, Wis., assignor to
Walker Manufacturing Company of Wisconsin,
Racine, Wis., a corporation of Wisconsin

Application August 4, 1944, Serial No. 114,741

Term of patent 14 years

(Cl. D41—1)

To all whom it may concern:

Be it known that I, Charles S. McCann, a citizen of the United States of America, residing in Racine, in the county of Racine, State of Wisconsin, have invented a new, original, and ornamental Design for a Dolly, of which the following is a specification, reference being had to the accompanying drawing, forming a part thereof, wherein:

Fig. 1 is a top plan view of a dolly showing my new design;

Fig. 2 is an end elevational view as seen from the right of Fig. 1; and

Fig. 3 is a side elevational view thereof.

The dominant features of my new design are shown in full lines in the drawing.

I claim:

The ornamental design for a dolly, substantially as shown and described.

CHAS. S. McCANN.
